APPARATUS FOR TREATING WAXED WEBS

Adolph Potdevin, Garden City, N. Y., assignor to
Potdevin Machine Company, Brooklyn, N. Y.,
a corporation of New York

Application May 31, 1935, Serial No. 24,294

11 Claims. (Cl. 91—18)

This invention relates to an apparatus for dissipating surface wax and is particularly directed to the dissipation or removal of portions of wax from waxed paper and the like.

5 My invention is particularly well adapted for the dissipation of spots or stripes of wax from waxed paper so as to accommodate or adapt the paper to receive adhesive in such spots or stripes whereby the making of bags, envelopes and the like is greatly facilitated.

In the making of bags and the like from a web of material such as paper, for example, a longitudinal stripe of adhesive is applied adjacent one edge of the web so that when the same 15 is formed into a tube, the adhesive stripe will overlie the opposed edge of the web and form a longitudinal seam. Likewise stripes or spots of adhesive are also applied transversely of the web whereby when a bag length is severed from 20 the tube one end may be folded over and secured to the body of the bag length to form a bottom.

When employing a web of waxed paper, however, the adhesive obviously will not adhere to the wax surface. My present invention contemplates the dissipation or removal of sufficient of 25 the wax surface at the desired points to enable adhesive to be applied thereto.

The accompanying drawing illustrates apparatus for carrying out my invention in which 30 drawing

Fig. 1 is a diagrammatic side view of the apparatus;

Fig. 2 is a plan view partly in section; and

Fig. 3 is an elevational view of a web of waxed 35 paper after being treated in my apparatus.

Referring to the drawing in detail, I designates a supply roll of waxed paper, the paper in web form being drawn continuously from this roll by draw rollers or other suitable mechanism 40 commonly used in paper handling machines, the paper passing about a roller 3 and thence about a cylinder 4.

The cylinder 4 is provided with a shell 5 having longitudinally extending channels 6, 7, 8 and 9 equally spaced therein circumferentially. These channels are adapted to receive removable heating elements 10, 11, 12 and 13, respectively, which are heated electrically as will be hereinafter explained. These heating elements contact the web 50 of waxed paper as the same passes about the cylinder 4 to dissipate or melt the surface wax where the paper contacts the heating elements to provide transverse stripes or unwaxed areas 14 in the paper. It will be obvious that if longer 55 stripes should be desired such as indicated in dotted lines at 15 in Fig. 3, it is merely necessary to remove the relatively short heating elements and substitute longer elements. Likewise, if shorter stripes or series of spots or any other formation of unwaxed surface is desired, bars cor-

responding to such formation may be substituted.

The heating or resistance elements 10, 11, 12 and 13 are in an electric circuit which may be traced as follows: From a source of supply through conductor 20, switch blade 21, conductor 22 to commutator brush 26, commutator ring 27, terminal 28, conductors 29 and 30, the heating element 10, conductors 33, 34, terminal 37, commutator ring 38, brush 39, conductors 40, 41, 42, switch blade 43 and conductor 44 to the other 10 side of the line. A circuit has been traced to the heating element 10. The other heating elements 11, 12 and 13 are tapped off conductors 29 and 34, and it is believed unnecessary to trace each of these individual circuits. It will be obvious 15 from the foregoing that upon the closing of switch 19, current will be supplied to the heating elements 10, 11, 12 and 13 thereby to dissipate the wax at certain areas of the paper corresponding to the location of the heating elements, these 20 areas eventually to receive adhesive as will be apparent hereinafter.

It is also necessary in preparing the waxed web for tubing to provide the web with a longitudinal unwaxed stripe 50 for receiving adhesive. 25 I accomplish this by providing an electrically heated disc 51 at one end of the cylinder. This disc may be removable so as to substitute wider or narrower discs to provide different width stripes, and receives its heating current from the 30 commutator ring 27 through conductor 52, the disc 51, conductor 53 and commutator ring 38.

It will be apparent from the description thus far that as the web passes about the cylinder 4 with the circuit closed, the web will be provided 35 with transverse stripes and with a longitudinal stripe adjacent one edge of the web where the wax has been dissipated.

The web next passes over a heating box 60 and from thence to a wax wiping device 61. The wax 40 wiping device comprises a disc of felt or other suitable material positioned so as to follow the longitudinal stripe 50 of the web, and as the web engages this disc, the dissipated or softened wax is removed leaving an area extending longitudinally of the web free of wax. 45

On the same shaft with the disc 61 I provide a roller 65 provided with a pad 66 of felt or other suitable material projecting radially therefrom and extending longitudinally of the roller. This 50 pad is of the same length and width as the softened spaces 14 left by the heating elements 10, 11, 12 and 13, and the speed of rotation of the roller 65 is so timed that the pad 66 will engage these 55 transverse spaces as the web advances, to remove the softened wax therefrom as the web passes over a roller 70 which lies adjacent the mechanism just described.

Below the wax removing mechanism just described I provide a trough 71 in which is mounted 60

an electrically heated roller 72. This roller contacts with the disc 61 and with the pad 66 so that the wax removed from the web by the disc and pad is transferred to the heated roller 72. A 5 scraper 73 engages the periphery of the heated roller 72 to remove the wax therefrom which falls or flows into the trough from which it may be drained through spout 74.

The heating element for the roller 72 receives 10 its energy from the electrical supply source above referred to and its circuit is closed when the switch 19 is closed.

After the web leaves the roller 70 it passes about rollers 80 and 81, thence past a paste applying device 82, which may be of the usual construction, where adhesive is applied in the spaces and stripe from which the wax has been removed.

The web then passes to tube forming mechanism, not shown, but which may be of usual construction.

While I have illustrated one embodiment of a device suitable for carrying out my invention, it is to be understood that various changes and modifications may be made therein without departing 25 from the spirit and scope of my invention.

What I claim is:—

1. Apparatus of the class described, comprising in combination means for effecting the continuous advance of a waxed paper web, heating elements in the path of said traveling web for fusing the surface wax of said web at spaced intervals, and means in the path of said web for subsequently removing the fused wax.

2. Apparatus of the class described, comprising 35 in combination means for effecting the continuous advance of a waxed paper web, a plurality of heating elements in the path of said advancing web for fusing the surface wax of said web at spaced intervals, means in the path of the web 40 for subsequently removing the fused wax, and means for subsequently applying adhesive to the web at the de-waxed areas.

3. Apparatus of the class described, comprising 45 in combination means for effecting the continuous advance of a waxed paper web, a plurality of electrically heated elements in the path of said advancing web for fusing the surface wax of said web at spaced intervals, means in the path of the web for subsequently removing the fused wax, and means for subsequently applying adhesive to the web at the de-waxed areas.

4. Apparatus of the class described, comprising 55 in combination means for effecting the continuous advance of a waxed paper web, electrically heated elements in the path of said traveling web for fusing the surface wax of said web at spaced intervals, and heated means in the path of said web for subsequently removing the fused wax.

5. Apparatus of the class described, comprising 60 in combination means for continuously advancing a web of waxed paper, a plurality of heating elements in the path of said traveling web for fusing the surface wax of said web at predetermined areas, means for subsequently removing the fused wax from said areas, and means in the path of said traveling web for maintaining the wax fused at said areas in its travel from said heating elements to said wax removing means.

6. Apparatus of the class described, comprising 65 a rotating drum, equally spaced heating elements

at the periphery of said drum, an electric circuit including said heating elements for energizing the elements, a disc in said electric circuit and heated thereby and carried by said drum, and means for drawing a web of waxed material about 5 said drum to effect fusing of the surface wax thereof at spaced areas corresponding to said heating elements and along an area corresponding to said disc, and extending continuously lengthwise of said web.

7. Apparatus for the treatment of waxed paper 10 comprising a rotatable drum, equally spaced heating elements removably secured in the periphery of said drum, an electric circuit including said heating elements for energizing the same, a disc 15 in said electric circuit and heated thereby and removably carried by said drum, and means for advancing said paper continuously about said drum in operative relation to said heating elements and disc, thereby to fuse the surface wax 20 of said paper at spaced areas corresponding to the location of said heating elements and along an area corresponding to said disc, and extending continuously lengthwise of the paper.

8. Apparatus for the treatment of waxed paper 25 comprising a rotating drum, equally spaced channels in the periphery of said drum, heating elements removably secured in said channels, an electric circuit including said heating elements for energizing said elements, a disc in said electric 30 circuit and heated thereby and removably secured to one end of said drum, and means for passing said paper about said drum to effect fusing of the surface wax of the paper at spaced intervals corresponding to said heating elements 35 and along an area corresponding to said disc, and extending continuously lengthwise of the paper.

9. Apparatus for the treatment of waxed paper 40 comprising a plurality of heating elements in the path of said web for fusing the surface wax of said web at spaced intervals, and a rotating member carrying a heated wiper for intermittent engagement with the surface of the web for removing the fused wax.

10. Apparatus for the treatment of waxed paper comprising a plurality of heating elements in the path of said traveling web for fusing the surface wax of said web at predetermined areas, and a roller in the path of the web, said roller 50 carrying heated pads and being so timed as to engage the fused areas for removing the fused wax, and means for applying adhesive to the web in the spaces from which the wax has been removed.

11. Apparatus for the treatment of waxed paper comprising a plurality of heating elements in the path of said traveling web for fusing the surface wax of said web at predetermined areas, a roller carrying wipers mounted in the path of the web, said wipers contacting the web at the fused areas for removing the wax thereat, a heated roller in contact with said wipers for maintaining the same heated and a scraper in engagement with said heated roller for removing the fused wax therefrom, and heated means intermediate said members and wipers for maintaining the fused surfaces molten during the travel of said web from said heating elements to said wax removing means.

ADOLPH POTDEVIN. 70
